(57) **CLAIM**

The ornamental design for a nose and ear clearing device, as shown and described.

DESCRIPTION

FIG. 1 is a top, front, right perspective view of a nose and ear clearing device, showing my new design;

FIG. 2 is a bottom, rear, left perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is an enlarged view of detail “9” identified in FIG. 1;

FIG. 10 is an enlarged view of detail “10” identified in FIG. 1; and,

FIG. 11 is an enlarged view of detail “11” identified in FIG. 2.

In the drawings, the equal-length broken lines depict unclaimed portions of the nose and ear clearing device that form no part of the claimed design.
